SEMISUBMERSIBLE MOTOR PUMP

Aladar Hollander, Los Angeles, Calif., assignor to
 Byron Jackson Co., Huntington Park, Calif.,
 a corporation of Delaware

Application September 12, 1938, Serial No. 229,508

6 Claims. (Cl. 172—36)

This invention relates generally to motor-driven deepwell pumps, and particularly to pumping units of the type wherein the motor and pump are suspended within the well from the discharge column, the pump being positioned below the normal pumping level and the motor being above the highest standing level of the well liquid.

Totally submersible motor pump units such as are in general use at the present time have many advantages over shaft-driven deepwell pumps wherein the motor is located at the top of the well. Aside from the advantages derived from the elimination of the long drive shaft, the motor housing is cooled by the flow of well liquid 10 13 16 19 22 25 28 31 34 37 40 43 46 49 52 55 58 61 64 67 70 73 the surface through a conductor cable 40 which enters the casing 4 through a pothead 41. The pothead is secured in fluid-tight relation to a tubular extension 42 formed integral with the cap 24 and projecting through an opening in the flange portion 43 of the fitting 3 in fluid-tight relation thereto. Within the pothead 41 the terminals of the conductors in the cable 40 are secured to the upper terminals of a short length of cable 44 connected at its lower end to the motor windings.

It is desirable that the motor housing be filled with a dielectric liquid, at least while running, to aid in dissipating the heat generated by the motor. It is well recognized that the rate of dissipation of heat from the motor through the housing to the stream of discharge liquid is much higher in an oil-filled motor than in an air-filled motor. However, difficulties have been experienced in prior attempts to provide an oil-filled motor when the rotor shaft projects through the lower end of the motor housing, due to the leakage of oil from the housing through the stuffing box around the shaft. I have overcome these difficulties by the arrangement described below.

The lower end of the reservoir is closed by a plate 48 formed integral with an upstanding sleeve 49 extending nearly to the upper end of the reservoir and closely surrounding the rotor shaft 50. The plate 48 is secured in fluid-tight relation to the reservoir 21 by a confined gasket 51 compressed by a nut 52 threaded to the lower end of the reservoir, to prevent leakage of well liquid from the discharge channel 22 into the reservoir. An annular reservoir is thus formed which normally contains oil or other dielectric liquid up to the level indicated at 53 when the motor is idle. A close-fitting, machined sliding fit is provided at 54 between the lower end of the reservoir and the upstanding flange 20, accurately centering the reservoir on the flanged fitting 6 and sealing off the discharge channel 22 from the interior of the flange 20.

An inverted sleeve member 55 is secured at its upper end in fluid-tight relation to the shaft 52 and extends downwardly around the sleeve 51 to adjacent the lower end of the reservoir. A pinion 57 is keyed to the shaft 52 above the sleeve 55 and meshes with a pinion 58 keyed to a shaft 59 journaled at its upper end in the bracket 32. The lower end of the shaft extends downwardly to a small pump 60, preferably a gear pump, mounted on the base plate 48. The inlet of the pump communicates with the reservoir 21 and connected to the discharge outlet thereof is a conduit 61 extending upwardly to the upper motor bracket 31, being connected thereto at 62 above the upper bearing 29. A baffle 63 is secured to the shaft 52 between the pinion 57 and the lower bearing 30, the baffle forming with the inner wall of the bracket 32 a throttle passage 64 restricting the drainage of oil from the motor housing back to the reservoir. A port 67 is formed in the flange 5 at the base of the casing 4 to establish communication between the air space of the well and the reservoir, whereby the latter is at atmospheric pressure.

The shaft 52 is journaled in a bearing bushing 68 in the flange 5, and extends downwardly to the pump. Surrounding the shaft between the fitting 6 and the discharge piece is a tube 70 for conducting lubricant to a sleeve bearing 71 in the discharge piece. A lubricant conduit 72 extends from the surface to a nut 73 to which the tube 70 is secured.

The mode of operation of the device is as follows: on energization of the motor 27 the pump 10 is actuated and discharges pump liquid upwardly through the lower column 7, the semi-annular passage in the fitting 8, thence into the 5 casing 4 and upwardly in the annular space 22 around the reservoir 21 and motor housing 23, thence through the fitting 3 and upper discharge column to the surface. During operation of the motor the gear pump 60 is driven by the shaft 10 52, drawing oil from the reservoir and forcing it upwardly to the upper end of the motor housing. After passing over the bearing 29 the oil works its way downwardly around the stator and through the rotor gap to the lower bearing 30 and thence through the throttle passage 64 and back to the reservoir. The area of the throttle passage is such that the rate of flow of oil there-through is less than the discharge capacity of the gear pump 60, and consequently the oil gradually collects above the bearing 30 and eventually fills the motor housing, the oil level in the reservoir being lowered to substantially the level indicated at 75. A dynamically balanced condition is then established, the increased static pressure 20 of the oil in the motor housing causing it to flow through the throttle passage at a faster rate than initially.

As soon as a layer of oil collects above the lower bearing 30, the air in the motor housing 30 would be entrapped therein, and would prevent filling the motor housing completely with oil. To avoid this an air vent tube 76 extends from the upper end of the motor housing downwardly in the space between the stator shell and the 35 housing and through the bracket 32 into the reservoir. This allows the complete interchange of oil and air between the motor housing and the reservoir, and provides an oil overflow when the oil level reaches the upper end of the vent tube. 40

It will be observed that the outer sleeve 55 dips into the oil in the reservoir at all times to provide a liquid seal preventing the admission of moisture-laden air from the well into the reservoir and thence into the motor housing. The inverted sleeve 55 also insures that none of the oil draining back to the reservoir enters the inner sleeve 49.

From the foregoing description it will be evident that I have provided a semisubmersible motor pump unit which possesses most of the advantages of a totally submersible unit but which is relatively inexpensive as compared to submersible units. Effective cooling of the motor and lubrication of the bearings is provided by the 50 continuous forced circulation of oil, and there is no danger of loss of oil such as is likely to occur through a stuffing box around the shaft. The pump shaft need be of a length only slightly greater than the normal draw-down of the well, 55 as compared to a shaft several hundred feet in length when the pump is operated by a motor at the surface.

I claim:

1. A semisubmersible motor comprising a substantially vertically extending housing having a fluid-tight closure at its upper end and a base having a centrally disposed shaft opening therein, an electric motor mounted in the upper portion of said housing and having a shaft extending 70 downwardly through the shaft opening in said base, a sleeve extending upwardly from said base in substantially concentric relation to said shaft and defining with the walls of said housing an annular reservoir containing a dielectric liquid, 75

a pump driven by said shaft for transferring liquid from the reservoir upwardly to said motor, and means between the motor and reservoir forming a restricted passage affording restricted flow of liquid from said motor back to said reservoir.

6. A semisubmersible motor comprising a substantially vertically extending housing having a closed upper end and a base having a shaft opening therein, an electric motor mounted in the upper portion of said housing and having a shaft extending downwardly through said shaft opening into operative engagement with a driven element outside of and below said housing, said base having a sleeve extending upwardly from said shaft opening in substantially concentric relation to said shaft to define an annular reservoir for dielectric liquid in the lower portion of said housing, a pump driven by said shaft for transferring dielectric liquid from the reservoir upwardly to said motor, means between the motor and reservoir forming a restricted passage affording flow of liquid at a restricted rate from said motor back to said reservoir, and a baffle beneath said restricted passage and overlying the space between said shaft and said sleeve.

3. A semisubmersible motor comprising a housing having a closed upper end and a base having a shaft opening therein, a partition extending transversely of said housing and dividing the latter into upper and lower compartments, an electric motor mounted in the upper compartment and having a drive shaft extending downwardly through said partition, lower compartment, and shaft opening, a sleeve extending upwardly from the base of said lower compartment in substantially concentric relation to said shaft and forming an annular reservoir, and means for maintaining said motor compartment substantially filled with dielectric liquid during, and only during, operation of the motor, comprising a supply of dielectric liquid normally maintained in said reservoir when said motor is idle, a pump

driven by said shaft for transferring said liquid to said motor compartment during operation of the motor, and a restricted passage in said partition affording restricted flow of said liquid back to said reservoir.

5

4. A semisubmersible motor as set forth in claim 3, in which said housing is mounted within an outer casing adapted to form part of a well discharge column whereby the walls of said housing are cooled by flow of well fluid past said housing.

10

5. A semisubmersible motor as set forth in claim 3, in which said housing is mounted within an outer casing adapted to form part of a well discharge column whereby the walls of said housing are cooled by flow of well fluid past said housing, the base of said housing being sealed in fluid-tight relation to said casing and the shaft opening in said base being in open communication with the exterior of said casing.

15

6. In combination in a semisubmersible structure, a substantially vertical housing having a transverse partition dividing it into an upper compartment and a lower compartment, a rotatable element in said upper compartment and a shaft connected to said element and extending downwardly through said partition and through said lower compartment, a sleeve extending upwardly from the base of said lower compartment in substantially concentric relation to said shaft and forming an annular reservoir, and means for maintaining said upper compartment substantially filled with lubricant during, and only during, rotation of said shaft, said means comprising a supply of lubricant normally maintained in said reservoir when said shaft is idle, a pump driven by said shaft for transferring lubricant upwardly to said upper compartment during operation of said shaft, and a restricted passage in said partition affording restricted flow of said lubricant back to said reservoir.
